UNITED STATES PATENT OFFICE.

SAMUEL PUTNAM, OF NEW YORK, N. Y.

TROLLEY-LADDER.

1,188,991.

Specification of Letters Patent. Patented June 27, 1916.

Application filed January 8, 1916. Serial No. 70,954.

To all whom it may concern:

Be it known that I, SAMUEL PUTNAM, a citizen of the United States, and a resident of the city of New York, borough of Brooklyn, in the county of Kings and State of New York, have invented a new and Improved Trolley-Ladder, of which the following is a full, clear, and exact description.

Among the principal objects which the present invention has in view are: to provide means for normally holding a ladder of the type mentioned in stationary position; to provide means for releasing the ladder to permit movement of the same to change the service location; and to provide a simplified and inexpensive mechanism for controlling the movement of the ladder.

Drawings.—Figure 1 is a side view of a top fragment of a ladder constructed and arranged in accordance with the present invention, the same being shown in conjunction with a fragment of overhead rail for supporting said ladder in service position; and Fig. 2 is a back view of a ladder having a track mechanism such as described.

Description.—As seen in the drawings, a truck 7 of conventional form is suspended from a hollow tubular track 8, the lower edges 9 of which are contracted to form a slot-like opening for the pendant legs 10. The legs 10 are pivotally connected to frames 11, using for this purpose, pins 12. The frames are permitted to rock on the legs 10 to allow the wheels 13 to accommodate any variation in the track 8. The wheels are suitably mounted on pins 14.

The ladder proper has side stringers 15 which are suitably connected by steps 16 of approved construction. Secured by a bolt 17 is a bracket 18. The bracket 18 is bifurcated to form bearings for a bell crank lever 19 and for the pivot pin 20 thereof. The lever 19 has a handle 21 which normally rests at the rear of the ladder and sufficiently remote from the next lower step thereof, to avoid engagement by the foot of a person using the ladder.

The truck 7 is preferably rigidly connected to or integrally formed with a tubular cross arm 22. In this way, the arm 22 is made rigid with the truck 7 and is thereby disposed to form a steady bearing for a pivot rod 23. The pivot rod 23 forms a pivotal bearing for the ladder and the stringers 15 thereof. To steady the bearing thus

formed, the ends of the cross-arm 22 are flared to form bearing plates 24. The plates 24 on the inner sides of each of the stringers 15 and the washers 25 at the outer sides of the said stringers, form substantial clamps 60 for the said stringers when the nuts 26 are set up on the screw-threaded end sections 27.

The truck 7 is normally held in fixed service relation by a wedge shoe 28. The shoe 28, as best seen in Fig. 2 of the drawings, has 65 a fin 29, which constantly remains between the edges 9 to serve as a guide for the truck. The shoe 28 is supported on a plunger 30, which is reciprocated in a bearing formed in the enlarged end 31 of the truck 7. 70

The means employed for reciprocating the plunger 30 comprises a spiral spring 32 which rests between the shoe 28 and the end 31, and a bell crank lever 33, which is pivotally mounted by a pin 34 on the truck 7 and directly upon a pendant bracket 35 thereon. The lower or free arm of the lever 33 is operatively connected with the free end of the lever 19 by a chain 36. 75

Operation.—When thus equipped, a ladder of the character denoted is normally held in stationary service by the spring 32 forcing the shoe 28 and fin 29 also between the edges 9 of the track 8. Thus the ladder is prevented from moving while a person is 85 entering thereon and in fact until he has reached a point in climbing the ladder to engage the handle 21. Having climbed to the position where he may manipulate the handle 21, the user of the ladder being prepared to move the same, grasps the handle 21 and rocks the lever 19 to draw downward on the lever 33. The lever 33 being thus rocked, depresses the plunger 30 and compresses the spring 32 until the shoe 28 and 90 fin 29 release their engagement of the track 8. While the operator now holds the handle 21 in the position described, the ladder may be freely moved on the track 8. When having arrived at a new desired service position, the operator releases the handle 21, the spring 32 lifts the shoe 28 into holding engagement with the edges 9 of the track 8. 95

The truck 7 is now prevented from being moved and a new service position of the ladder becomes fixed until the operator again manipulates the handle 21 of the lever 19. 100

Claim:

A trolley ladder comprising a tubular overhead track; a wheel-supported truck 110

mounted within said tubular track to move lengthwise thereof; a brake mounted on said truck, said brake having a wedge-shaped member for partially entering to engage said track; a spiral spring supporting said wedge-shaped member; a plunger; a bell crank lever operatively connected with said brake to separate the head thereof from engagement with the overhead track; and means for operating said lever, said means

embodying a handle disposed adjacent the upper end of said ladder.

In testimony whereof I have signed my name to this specification in the presence of two subscribing witnesses.

SAMUEL PUTNAM.
